UNITED STATES PATENT OFFICE.

JOSEPH B. STRAUSS, OF CHICAGO, ILLINOIS.

AMUSEMENT DEVICE.

1,420,887.

Specification of Letters Patent. Patented June 27, 1922.

Application filed November 5, 1919. Serial No. 335,899.

To all whom it may concern:

Be it known that I, JOSEPH B. STRAUSS, a citizen of the United States, residing at Chicago, in the county of Cook and State 5 of Illinois, have invented a certain new and useful Improvement in Amusement Devices, of which the following is a specification.

This invention relates to amusement devices and has for its object to provide a new 10 and improved device of this description. One of the objects of the present invention is to provide an amusement device wherein the cars in which the passengers are carried are suspended below the track along which 15 they travel, the parts being arranged so that when the cars are taken to the top of the device they will run by gravity around the system to the point where the passengers are discharged and received. The invention 20 has other objects which are more specifically pointed out in the following description. The invention is illustrated in the accompanying drawings, wherein—

Fig. 1 is a plan view showing an amusement device embodying the invention;

Fig. 2 is a sectional view taken on line 2—2 of Fig. 1;

Fig. 3 is an elevation showing a part of the structure;

Fig. 4 is a sectional view taken on line 4—4 of Fig. 1;

Fig. 5 is an enlarged view illustrating the method of supporting the cars;

Fig. 6 is a side view of the car;

Fig. 7 is a detail of the drive.

Like numerals refer to like parts throughout the several figures.

In carrying out the invention I provide a supporting framework 1 for the cars which 40 may be arranged in any desired manner and which as shown in Fig. 1 curves and crosses different elevations. As illustrated in Fig. 1 there is a station 2 for the passengers in order to enter the cars. The supporting 45 framework consists of the posts 3 which are of different heights along the supporting framework. At the top of these posts are upright supports 4 preferably in the form of trusses to which are connected the cross 50 bracing or supports 5. The cross bracing carries the rails or tracks 6 for the wheels 7, said wheels being connected to the cars 22, said cars being suspended below the cross bracing and having portions 9 which extend 55 up through openings in the cross bracing, so as to make the connection in the wheels.

The cross bracing is provided with open spaces for the wheels which run on the rails or tracks 6. The rails are preferably parallel with the trusses 4. These trusses are 60 preferably deepened at their ends so that the cars pass between them as shown for example in Fig. 4, the cars at this point being located between the cross bracing and the top of the post. In Fig. 2 which is a section at 2—2 of Fig. 1, there is illustrated a part of the structure where one set of tracks is above the other. In this construction there are two posts 3^a the lower tracks being suspended between these posts. A single 70 post 3^a is mounted on these two posts and the other set of tracks are at the end of this single post 3^a. The cars are also provided with safety devices 10 which extend up through these openings and project over the 75 rails 6 so that if the connection between the cars and the trucks fail these safety devices will drop on the rails and still support the cars so as to prevent accidents. Certain of the posts 3 may be connected together by 80 the cross members 3^a where this can be done, so as to make a more stable structure. There are preferably two of such rails and two of such cars connected with each cross support 5.

The cars are pulled up to the top or highest part of the structure by some suitable mechanism and are then released and run by gravity along the rest of the structure. Any suitable mechanism for pulling up the cars 90 may be used. As shown for example in Fig. 7 there is a chain or belt 11 which passes around suitable direction changing devices and has suitable guiding devices 13. This belt is provided with a series of hooks or 95 engaging devices 14 which engage hooks or engaging devices 15 on the cars. The cars are loaded at the station 2 or the platform 2^a and then are run by gravity around to the point 16 where the engaging devices 14 engage the engaging devices 15, whereupon the cars are pulled up the incline by the belt. This belt is operated in any desired manner as by means of the motor 17 which drives a shaft 18 about which the endless belt 100 passes. When the cars are pulled up to the proper point by the belt 11 they are then released and move along the supporting framework by gravity till they reach the point where the passengers are discharged, 110 that is the station 2 or platform 2^a. The two sets of cars run together and in addition

to the ordinary speed effect there is also provided a racing effect between the two sets of cars.

The path of the supporting framework 5 may be arranged as desired. In the construction illustrated a portion of the framework passes through tunnels 19 and 20^a there being an intermediate lagoon 21^a through which the cars travel. The bottoms 22 of 10 the cars are preferably arranged in boat form so that they can pass through the water lagoon without having any of the water enter the cars.

Lateral guides are provided for the cars 15 to prevent their swinging and to guide them in the proper pathway. One form of these guides is illustrated in Fig. 5 wherein there is connected to the cross bracing on opposite sides of the cars the guides 20 and there are 20 engaging devices 21 on the cars which engage these guides.

I claim:

1. A railway comprising two separated longitudinal trusses forming the exterior 25 boundaries of the upper part of the structure, the space between said trusses being free from longitudinal structural supporting members, cross bracing extending across the space between said longitudinal trusses 30 and connecting them, two pairs of rails carried by said cross bracing between the trusses and parallel thereto, open spaces in said cross bracing above said rails, wheels in said open spaces and running on said 35 rails, and cars located beneath said rails and connected with said wheels.

2. A railway comprising two separated longitudinal trusses forming the exterior 40 boundaries of the upper part of the structure, the space between said trusses being free from longitudinal structural supporting members, posts upon which said trusses are supported, cross bracing extending across the space between said longitudinal trusses 45 and connecting them, two pairs of rails carried by said cross bracing between the trusses

and parallel thereto, open spaces in said cross bracing above said rails, wheels in said open spaces and running on said rails, cars located beneath said rails, said cars connected with said wheels. 50

3. A railway comprising two separated longitudinal trusses, posts upon which said trusses are supported, cross bracing connecting said trusses, two pairs of rails carried by said cross bracing between the trusses and parallel thereto, open spaces in said cross bracing above said rails, wheels in said open spaces and running on said 55 rails, cars located beneath said rails, said cars connected with said wheels, said trusses deepened at their ends so as to pass along the sides of the cars, said cars being located between the cross bracing and the top of the post. 60

4. A railway comprising separated trusses, posts upon which said trusses are mounted, cross bracing connecting with said trusses, rails carried by said cross bracing, wheels on said rails, a car connected with said wheels 70 and suspended below said cross bracing, lateral connecting devices for said cross bracing, guides connected with the cross bracing and engaging devices engaging said guides and connected with said car near the top 75 thereof.

5. A railway comprising two separated longitudinal trusses, cross bracing between the trusses, two pairs of rails carried by said cross bracing, open spaces in said cross bracing and above said rails, wheels in said open 80 spaces and mounted on said rails, and longitudinal guides connected with the cross bracing for guiding said wheels.

In testimony whereof, I affix my signature 85 in the presence of two witnesses this 23rd day of October, 1919.

JOSEPH B. STRAUSS.

Witnesses:

EDNA B. PETERSON,
MINNIE M. LINDENAU.
